REFRIGERATION CONTROL SYSTEM

William L. McGrath, St. Paul, Minn., assignor to
 Minneapolis-Honeywell Regulator Company,
 Minneapolis, Minn., a corporation of Delaware

Application December 3, 1938, Serial No. 243,808

27 Claims. (Cl. 62—4)

This invention relates to a control system for a refrigerating apparatus and particularly to a control system for accomplishing defrosting of the cooling coils of the refrigerating apparatus.

It is an object of this invention to provide a control system for a refrigerating apparatus wherein valve means control the circulation of refrigerant through the cooling coil and wherein the valve means is controlled by space temperature and the defrosted condition of the cooling coil, the arrangement being such that upon a call for cooling the valve means is opened only when the cooling coil has defrosted.

Another object of this invention is to apply the above control arrangement to the cooling coils of a multiple fixture refrigerating apparatus to obtain individual temperature and defrosting control in each fixture even though the cooling fluid is supplied to the various fixtures by a common circulating means.

Still another object of this invention is to apply the above control arrangement to those fixtures of a multiple fixture refrigerating apparatus that require defrosting and to control in a conventional manner those fixtures in which defrosting is not desirable whereby individual temperature control of all of the fixtures may be obtained while defrosting control of only part of the fixtures is afforded, all of the fixtures being supplied with cooling fluid from a common source.

Further objects of this invention reside in the novel manner in which the above sequences of control are accomplished.

Other objects and advantages of this invention will become apparent to those skilled in the art upon reference to the accompanying specification, claims, and drawings, in which:

Figure 1 is a diagrammatic illustration of one form of this invention applied to a multiple fixture refrigerating system to obtain individual temperature and defrosting control of each fixture.

Figures 2 and 3 are diagrammatic illustrations of valves which may be substituted in the system of Figure 1 for obtaining the desired sequence of control, and

Figure 4 is a diagrammatic illustration of a modified control arrangement wherein individual temperature control of the fixtures is obtained and wherein defrosting control of certain of the fixtures is also obtained.

Referring now to Figure 1, a plurality of fixtures to be cooled are illustrated at 10, 11, and 12 which may be rooms, walk-in boxes, freezer units, soda fountains, and the like. The fix-

tures 10, 11, and 12 are cooled by cooling means in the form of evaporators 13, 14, and 15, respectively. Refrigerant is circulated through the evaporator means 13, 14, and 15 by means of a common refrigerating apparatus generally designated at 16 and which may comprise a compressor 17 operated by a motor 18. Compressed refrigerant is delivered by the compressor 16 through a high pressure line 19 into a condenser 20 and condensed refrigerant is collected in a receiver 21. Liquid refrigerant flows from the receiver 21 through a liquid line 22 to the evaporators 13, 14, and 15. Evaporated refrigerant is withdrawn from the evaporators 13, 14, and 15 through a suction line 23 by the compressor 16. It is here noted that the evaporators 13, 14, and 15 are connected in a parallel relation to the refrigerating apparatus 16.

The flow of liquid refrigerant through the evaporators 13, 14, and 15 is regulated by the usual expansion valves 25, 26, and 27, respectively. The circulation of refrigerant through the evaporators 13, 14, and 15 is also controlled by solenoid valves 28, 29, and 30, respectively, located at the outlet of each evaporator. If desired the circulation of refrigerant through the evaporators 13, 14, and 15 may also be controlled by solenoid valves 31, 32, and 33, respectively, located in the liquid lines ahead of the expansion valves leading to the evaporators.

The solenoid valves 28 and 31 of the fixture 10 are controlled by a relay 35, the solenoid valves 29 and 32 of the fixture 11 are controlled by a relay 36, and the solenoid valves 30 and 33 of the fixture 12 are controlled by a relay 37. The relay 35 associated with the fixture 10 is controlled by a temperature responsive controller 38 responsive to the temperature within the fixture 10 and a defrosted condition responsive controller 39 responsive to the frost conditions of the evaporator 13. In a like manner the relay 36 associated with fixture 11 is controlled by a temperature responsive controller 40 and a defrosted condition responsive controller 41 and the relay 37 associated with the fixture 12 is controlled by a temperature responsive controller 42 and a defrosted condition responsive controller 43.

Since the defrosted condition of the evaporators is reflected by the pressure within the evaporators, the defrosted condition responsive controllers 39, 41, and 43 may be made responsive to the pressures existing within the evaporators 13, 14, and 15, respectively.

The operation of the compressor motor 18 and hence the compressor 17 may be controlled by a

suction pressure controller 45 responsive to the pressure on the low pressure side of the refrigerating apparatus and a head pressure controller 46 responsive to the pressure on the high pressure side of the refrigerating apparatus.

The relay 35 associated with the fixture 10 may comprise an operating coil 48 for operating switch arms 49, 50, and 51 with respect to stationary contacts 52, 53, and 54. Upon energization of the operating coil 48 the switch arms 49, 50, and 51 are moved into engagement with their respective contacts and when the operating coil 48 is deenergized the switch arms are moved out of engagement with their respective contacts by means of springs, gravity, or other means (not shown). The construction of the relays 36 and 37 of the fixtures 11 and 12 is exactly the same as that of the relay 35 and accordingly like reference characters for like parts have been utilized.

The temperature responsive controller 38 responding to the temperature within the fixture 10 may comprise a bellows 56 charged with a volatile fluid for operating a lever 57 against the action of an adjustable tension spring 58, the lever 57 operating a mercury switch 59. For purposes of illustration it is assumed that when the temperature within the fixture 10 rises to 42° the mercury switch 59 is tilted to the closed or on position and when the temperature decreases to 40° the mercury switch is tilted to the open or off position shown in Figure 1. The temperature responsive controllers 40 and 42 responsive to the temperature within the fixtures 11 and 12, respectively, are in all respects the same as the temperature responsive controller 38 and therefore like reference characters for like parts have been utilized. It is obvious that the temperature responsive controllers 40 and 42 may be adjusted for any temperature setting so that differing temperatures may be obtained in the three fixtures 10, 11, and 12 and such is within the scope of this invention.

The defrosted condition responsive controller 39 associated with the fixture 10 may comprise a bellows 61 connected by a pipe 62 between the evaporator 13 and the solenoid valve 28 so as to respond to the pressure within the evaporator 13. The bellows 61 operates a lever 63 against the action of an adjustable tension spring 64. The lever 63 operates contacts 65 and 66 with respect to adjustable stationary contacts 67 and 68. The contacts are so arranged that upon an increase in pressure they are sequentially engaged and upon a decrease in pressure they are sequentially disengaged. For purposes of illustration it is assumed that the contact 65 engages and disengages the contact 67 at 15 lbs. and the contact 66 engages and disengages the contact 68 at 35 lbs. The construction of the defrosted condition responsive controllers 41 and 43 is exactly the same as that of the defrosted condition responsive controller 39 and accordingly like reference characters have been utilized for like parts. For purposes of illustration it is assumed that when the pressure in the evaporators 13, 14, and 15 rises to 35 lbs. these evaporators have defrosted so that when the contacts 66 and 68 engage this is an indication of the fact that the evaporators have defrosted.

The suction pressure responsive controller 45 may comprise a bellows 70 connected by a pipe 71 to the suction pressure line 23 for operating a lever 72 against the action of an adjustable

tension spring 73. The lever 72 operates a mercury switch 74 and for purposes of illustration it is assumed that the mercury switch 74 is moved to a closed position when the suction pressure increases to 30 lbs. and is moved to an open position as shown in Figure 1 when the suction pressure decreases to 10 lbs. Accordingly the suction pressure is at all times maintained between 10 and 30 lbs. by the suction pressure responsive controller 45.

The head pressure responsive controller may comprise a bellows 76 connected by a pipe 77 to the high pressure line 19 for operating a lever 78 against the action of an adjustable tension spring 79. The lever 78 operates a mercury switch 80 and for purposes of illustration it is assumed that the mercury switch 80 is tilted to the off position when the pressure on the high pressure side of the refrigerating apparatus increases to 180 lbs.

Power is supplied to the compressor motor 18, to the various solenoid valves and to the control system by means of line wires 82 and 83 leading from some source of power (not shown). 25 When the suction pressure rises to 30 lbs., a circuit is completed from the line wire 82 through wire 85, mercury switch 74, wires 86 and 87, mercury switch 80, wire 88, compressor motor 18, and wire 89 back to the other line wire 83. Completion of this circuit causes operation of the compressor 17 and the compressor remains in operation until the suction pressure decreases to 10 lbs., or the pressure on the high pressure side of the refrigerating apparatus increases to 180 35 lbs. In this manner the compressor 17 is operated to maintain the suction pressure between 10 and 30 lbs. and is shut off in case the head pressure increases to a high value of 180 lbs.

Assuming now that the temperature within 40 the fixture 10 rises to 42° to close the switch 59 and that the evaporator 13 has defrosted causing the contacts 65 and 66 to engage the contacts 67 and 68, a circuit is thereupon completed from the line wire 82 through wire 91, mercury switch 45 59, wire 92, contacts 67, 65, and 68, wire 93, operating coil 48 and wire 94 back to the other line wire 83. Completion of this circuit energizes the operating coil 48 to move the switch arms 49, 50, and 51 into engagement with the contacts 50 52, 53, and 54, respectively.

Movement of the switch arm 50 into engagement with the contact 53 completes a circuit from the line wire 82 through switch arm 50, contact 53, wires 95 and 96, solenoid valve 28, 55 and wires 97 and 98 back to the other line wire 83. Accordingly when the relay 35 is pulled in the solenoid valve 28 is opened. The solenoid valve 31 is connected in parallel with the solenoid valve 28 by means of wires 99 and 100 and hence when the solenoid valve 28 is opened upon pulling in of the relay 35 the solenoid valve 31 is likewise opened. It follows then that when the relay 35 is pulled in, the evaporator 13 of the fixture 10 is cut-in to the refrigerating system to cool the fixture 10.

Movement of the switch arm 49 into engagement with the contact 52 completes a maintaining circuit for the operating coil 48 which is independent of the contacts 65 and 66 of the frost condition responsive controller 39, this circuit being traced from the line wire 82 through wire 91, mercury switch 59, wire 92, contacts 67 and 65, wire 101, contact 52, switch arm 49, wire 102, operating coil 48, and wire 94 back to the other line wire 83. Completion of this maintaining

circuit maintains the solenoid valves 28 and 31 open until either the temperature within fixture 10 decreases to 40° or the pressure within the evaporator 13 decreases to 15 lbs. When either of these contingencies occur, the solenoid valves 28 and 31 are closed and cannot be again reopened until the temperature within the fixture 10 increases to 42° and the pressure in the evaporator 13 has increased to 35 lbs. indicating that the evaporator has defrosted. By reason of this arrangement the temperature within the fixture 10 is maintained within desired limits and the evaporator 13 is defrosted each time that the solenoid valves 28 and 31 are closed. Frost free temperature control within the fixture 10 is therefore obtained.

The various circuit connections between the temperature responsive controller 40, the defrosted condition responsive controller 41, the relay 36, and the solenoid valves 29 and 32 associated with fixture 11 and the various circuit connections between the temperature responsive controller 42, the defrosted condition responsive controller 43, the relay 37 and the solenoid valves 30 and 33 associated with the fixture 12 are the same as those outlined above in connection with those of fixture 10 and therefore like reference characters for like circuit connections have been utilized. In other words, the solenoid valves 29 and 32 associated with fixture 11 and the solenoid valves 30 and 33 associated with fixture 12 are operated in exactly the same manner as the solenoid valves 28 and 31 associated with fixture 10. Accordingly individual temperature and defrosting control for each fixture is obtained. Any temperature responsive controller can call for cooling and open its associated solenoid valves providing its evaporator is defrosted regardless of whether the other temperature responsive controllers are calling for cooling or are satisfied.

The switch arm 51 and the contact 54 of the relays 35, 36, and 37 may be located in parallel with the low pressure responsive controller 45 to cause operation of the compressor 17 when any of the solenoid valves are opened. For example assume that the relay 35 associated with fixture 10 is pulled in to open the solenoid valves 25 to 28, a circuit is completed from the line wire 82 through switch arm 51, contact 54, wires 105, 106, 107, and 87, mercury switch 80, wire 88, compressor motor 18 and wire 89 back to the other line wire 83. The switch arm 51 and contact 54 of the relay 36 and the switch arm 51 and contact 54 of the relay 37 are located in parallel with the switch arm 51 and contact 54 of the relay 35 by means of wires 108 and 109, respectively, so that when any of the relays are pulled in, the compressor 17 is operated. If this auxiliary switching mechanism is utilized it may be desirable to locate the suction pressure responsive controller 45 in series therewith instead of in parallel as shown to prevent the suction pressure from decreasing below a predetermined value and such a modification is within the contemplation of this invention.

Referring now to Figure 2, a valve is generally designated at 115 and may be substituted for the valves 28, 29, and 30 of Figure 1 to perform substantially the same sequence of operation as is accomplished in Figure 1. The valve 115 may comprise a valve casing 116 divided by a partition 117 into a chamber 118 connected to the evaporator 13 and a chamber 119 connected to the suction side of the compressor. The partition 117 is provided with a port 120 controlled by a valve

121 to control the communication between chambers 118 and 119. Mounted on the valve casing 116 is another casing 122 provided with a cover 123. Sealed to the casing 122 are concentrically located bellows 124 and 125 which are in turn sealed to a plate 126. The space between the bellows 124 and 125 is connected by a capillary tube 127 to a bulb 128 which may be located within the fixture being cooled. The bulb 128 is charged with a volatile fluid so that the plate 126 is moved upwardly upon an increase in temperature and is moved downwardly upon a decrease in temperature. The plate 126 is connected by a valve stem 129 to the valve 121 so that the valve 121 is moved concurrently with movement of the plate 126. A spring 131 located between the plate 126 and a spring retainer 132 carried by an adjusting screw 133 is utilized for urging the valve 121 towards its seat. By adjusting the adjusting screw 133 the temperature setting of the instrument may be adjusted at will to maintain desired temperature conditions within the fixture.

A plate 135 suitably secured to the valve casing 116 has sealed thereto one end of a bellows 136, the other end being sealed to a plate 137. A spring 138 located in the bellows 136 between the plate 137 and a spring retainer 139 carried by an adjusting screw 140 urges the plate 137 towards the right. The plate 137 carries an abutment 141 adapted to engage a notch 142 in the valve stem 129. The abutment 141 is guided by a member 143 slidably engaging a lug 144 formed in the valve casing 116. The abutment 141 and notch 142 form a latch for holding the valve 121 against the valve seat 120. When the temperature in the fixture increases an upward force on the valve stem 129 is exerted by the plate 126 but the valve 121 cannot open since it is latched closed by the abutment 141 engaging the slot 142. When the evaporator pressure has risen sufficiently to indicate that the evaporator has defrosted the plate 137 is moved to the left to release the abutment 141 from the notch 142 whereupon the valve 121 is opened to cut the evaporator into the refrigeration circuit. Immediately the pressure in the evaporator decreases but the abutment member 141 cannot engage the notch 142 since the notch 142 is not in alignment with the abutment 141 when the valve 121 is opened. When the temperature in the fixture decreases to the desired value the valve 121 is closed and the abutment 141 then engages the notch 142 to latch the valve closed. Accordingly the valve cannot again be reopened upon an increase in fixture temperature until the evaporator has defrosted. In order that the valve 121 may operate freely after the abutment 141 has been released it may be desirable to insert a strain release between the bellows plate 137 and the abutment member 141. From the above it is seen that the valve mechanism is operated in substantially the same manner as the solenoid valves of Figure 1 and accordingly the valve mechanism of Figure 2 may be substituted for the valve mechanisms of the system shown in Figure 1.

Figure 3 discloses a valve arrangement for accomplishing substantially the same results as are accomplished by the valve arrangement of Figure 2. The same valve casing and pressure responsive device is utilized in the valve mechanism 150 of Figure 3 as in the valve mechanism 115 of Figure 2 and accordingly like reference characters have been utilized for like parts. In Figure 3 a plate 152 is secured to the top of the valve casing 116, the plate being provided with a tube 153 upon

which is mounted an operating coil 154. A casing 155 secured to the plate 152 encloses the tube 153 and the operating coil 154. The upper end of the valve stem 129 is provided with a collar 157 engaged by a spring 158 for urging the valve 121 to its seat 120. A spring 159 is interposed between the collar 157 and an armature 160 slidably mounted on the valve stem 129. The spring 159 is stronger than the spring 158 when compressed so that when the armature 160 is moved upwardly 10 the spring 159 overcomes the spring 158 to open the valve 121. When the armature 160 drops to the position shown in Figure 3 the spring 158 closes the valve 121.

The operating coil 154 may be controlled by a 15 temperature responsive controller 38 which may be the temperature responsive controller located in the fixture 10 of Figure 1. When the temperature affecting the temperature responsive controller rises to a predetermined value, for example 42°, the mercury switch 59 is closed to complete a circuit from the line wire 162 through mercury switch 59, wire 163, operating coil 154 and line wire 164. Completion of this circuit energizes the operating coil 154 to move the armature 160 upwardly compressing the spring 159. The valve stem 129 however is prevented from moving upwardly by the latch means formed by the abutment 141 and the notch 142. When the evaporator has defrosted the abutment member 141 disengages the notch 142 and the spring 159 opens the valve 121 thereby cutting the evaporator into the refrigeration circuit. Immediately the pressure in the evaporator decreases but the abutment member does not engage with the notch 142 inasmuch as the valve 121 is opened. When the temperature within the fixture decreases, to say 40°, the mercury switch 59 is opened to deenergize the operating coil 154 whereupon the armature 160 moves downwardly to the position shown in Figure 3 and the spring 158 closes the valve 121. Upon closing of the valve 121 the abutment 141 engages the notch 142 to prevent reopening of the valve 121 until the evaporator has defrosted. The purpose of the spring 159 is to allow the armature 160 to move upwardly even though the valve 121 is latched closed thus preventing overheating of the operating coil 154.

Referring now to Figure 4, two fixtures in which a defrosting action is required are designated at 170 and 171 while a single fixture in which no defrosting is desirable is designated at 172. The fixtures 170 and 171 may be rooms, walk-in boxes, or the like while the fixture 172 may be a freezing compartment, ice cream freezer, or the like. The fixtures 170, 171, and 172 are cooled by cooling coils in the form of evaporators 173, 174, and 175, respectively. Refrigerant is circulated through the evaporators by a refrigerating apparatus generally designated at 176 which may comprise a compressor 177 operated by an electric motor 178. The compressor 177 delivers compressed refrigerant through a high pressure line 179 into a condenser 180 and the condensed refrigerant is collected in a receiver 181. Liquid refrigerant flows from the receiver 181 through a liquid line into the evaporators 173, 174, and 175 and evaporated refrigerant is withdrawn from the evaporators through a suction line 183 by the compressor 177. It is here noted that the various evaporators are connected in parallel with respect to each other into the refrigerating system. The circulation of the refrigerant through the evaporators 173, 174, and 175 is regulated by expansion valves 184, 185, and 186, respectively. Solenoid

valves 187, 188, and 189 control the supply of refrigerant to the evaporators 173, 174, and 175, respectively.

A pressure regulating valve 191 provided with a bypass 192 and a manual valve 193 may be located in the suction line leading from the evaporators 173 and 174 to regulate the pressure existing within these evaporators. A solenoid valve 194 is located between the evaporators 173 and 174 and the pressure regulating valve 191 and when this valve is closed communication between the suction side of the compressor and the evaporators 173 and 174 is interrupted.

The solenoid valves 187, 188, and 189 are controlled by temperature responsive controllers 196, 197, and 198, respectively, responsive to the temperature conditions within the fixtures 170, 171, and 172. The solenoid valve 194 in the suction line leading from the evaporators 173 and 174 is controlled by a relay generally designated at 199 and this relay is in turn controlled by a defrosted condition responsive controller in the form of a suction pressure responsive controller 200 responsive to the pressure in the evaporators 173 and 174 and the temperature responsive controllers 196 and 197 arranged in parallel with respect to each other.

A relay 201 which controls the operation of the compressor motor 178 and hence the compressor 177 is in turn controlled by a head pressure controller 202 responsive to the pressure on the high pressure side of the refrigerating apparatus by a suction pressure controller 203 responsive to the pressure on the low pressure side of the refrigerating apparatus, by the temperature responsive controller 198 in the fixture 172 and by a switch included in the relay 199.

The temperature responsive controller 196 responding to the temperature within the fixture 40 170 may comprise a bellows 205 charged with a volatile fluid for operating a lever 206 against the action of an adjustable tension spring 207. The lever 206 operates a mercury switch 208 provided with three electrodes at one end thereof. For purposes of illustration it is assumed that when the temperature within the fixture 170 rises to 42° the switch 208 is tilted to a position to cause the mercury therein to bridge the three electrodes and when the temperature within the fixture decreases to 40° the mercury switch 208 is tilted to the open position as shown in Figure 4. The temperature responsive controllers 197 and 198 are exactly like the temperature responsive controller 196 and accordingly like reference characters for like parts have been utilized. It is evident that the temperature responsive controller 197 may respond to different temperature values than the temperature responsive controller 196 and since the fixture 172 is utilized, for example, as a freezing fixture it is evident that the temperature responsive controller 198 will most likely respond to much lower temperatures, say 26 to 28°.

The relay 199 which controls the operation of the solenoid valve 194 may comprise an operating coil 210 for moving switch arms 211, 212, and 213 into engagement with contacts 214, 215, and 216, respectively, upon energization thereof. When the operating coil 210 is deenergized the switch arms are moved out of engagement with their respective contacts by means of springs, gravity, or other means (not shown).

The suction pressure responsive controller 200 responding to the pressure within the evaporators 173 and 174 and hence the defrosted condition of

these evaporators may comprise a bellows 218 connected by a pipe 219 to the suction pressure line between the evaporators 173 and 174 and the solenoid valve 194. The bellows 218 operates a lever 220 against the action of an adjustable tension spring 221 for closing a mercury switch 222 when the pressure increases to 35 lbs., illustratively, which corresponds to a defrosting temperature.

The relay or starter 224 which controls the operation of the compressor motor 178 and hence the compressor 177 may comprise an operating coil 224 for moving a switch arm 225 into engagement with a contact 226 when energized. When the operating coil 224 is deenergized the switch arm 225 is moved out of engagement with the contact 226 by means of springs, gravity, or other means (not shown).

The suction pressure responsive controller 203 may comprise a bellows 228 connected by a pipe 229 to the suction pressure line 183 adjacent the compressor 177 for operating a lever 230 against the action of an adjustable tension spring 231. The lever 230 opens a mercury switch 232 when the pressure on the low pressure side of the refrigerating apparatus decreases to, illustratively, 10 lbs.

The head pressure controller 202 may comprise a bellows 234 connected by a pipe 235 to the high pressure line 179 for operating a lever 236 against the action of an adjustable tension spring 237. The lever 236 opens a mercury switch 238 when the pressure on the high pressure side of the refrigerating apparatus increases to, illustratively, 180 lbs.

Power is supplied to the compressor motor 178, the various solenoid valves and to the control system by means of line wires 240 and 241 leading from some source of power (not shown).

Assume now that the temperature within the fixture 172 rises to 28°, to close the mercury switch 208, a circuit is thereupon completed from the line wire 240 through wire 242, mercury switch 208, wire 243, solenoid valve 189, and wire 244 back to the other line wire 241. Completion of this circuit opens the solenoid valve 189 to permit circulation of refrigerant through the evaporator 175. Closing of the mercury switch 208 of temperature responsive controller 198 also completes a circuit from the line wire 240 through wire 242, mercury switch 208, wires 245 and 246, mercury switch 238, wire 247, mercury switch 232, wire 248, operating coil 224 of the relay or starter 201 and wire 249 back to the other line wire 241. Completion of this circuit energizes the operating coil 224 as long as the temperature responsive controller 198 is calling for cooling, the pressure on the high pressure side of the refrigerating apparatus is below 180 lbs. and the pressure on the low pressure side of the refrigerating apparatus is above 10 lbs. Energization of the operating coil 224 moves the switch arm 225 into engagement with the contact 226 to complete a circuit from the line wire 240 through wire 250, switch arm 225, contact 226, wire 251, compressor motor 178 and wire 252 back to the other line wire 241. Completion of this circuit operates the compressor motor 178 and hence the compressor 177 to circulate refrigerant through the evaporator 175 to cool the fixture 172. When the temperature within the fixture 172 decreases to 26° the mercury switch 208 is tilted to the open position to close the solenoid valve 189 and to stop operation of the compressor 177.

Assume now that the temperature within the fixture 170 rises to 42° to close the mercury switch 208, a circuit is thereupon completed from the line wire 240 through wire 254, mercury switch 208, wire 255, solenoid valve 187, and wire 256 back to the other line wire 241. Completion of this circuit opens the solenoid valve 187 to permit the flow of refrigerant into the evaporator 173. When the evaporators 173 and 174 are defrosted to allow the pressure therein to rise to 35 lbs. to close the mercury switch 222 of the frost condition responsive controller 200, a starting circuit is completed from the line wire 240 through wire 254, mercury switch 208, wires 257, 258, and 259, mercury switch 222, wire 260, operating coil 210, and wire 261 back to the other line wire 241. Completion of this circuit energizes the operating coil 210 to pull in the relay 199.

Movement of the switch arm 212 into engagement with the contact 215 upon pulling in of the relay 199 completes a circuit from the line wire 142 through wires 263 and 264, contact 215, switch arm 212, wire 265, solenoid valve 194, and wires 266 and 261 back to the other line wire 241. Completion of this circuit opens the solenoid valve 194 to establish communication between the evaporators 173 and 174 and the suction pressure side of the compressor 177 whereupon refrigerant is allowed to flow through the evaporator 173.

Movement of the switch arm 213 into engagement with the contact 216 upon pulling in of the relay 199 completes a circuit from the line wire 240 through wires 263 and 268, contact 216, switch arm 213, wires 269 and 246, mercury switch 238, wire 247, mercury switch 232, wire 248, operating coil 224 of the relay or starter 201 and wire 249 back to the other line wire 241. Completion of this circuit pulls in the relay or starter 201 to operate the compressor 177 as long as the relay 199 is pulled in providing the head pressure is below 180 lbs. and the suction pressure is above 10 lbs.

Movement of the switch arm 211 into engagement with the contact 214 upon pulling in of the relay 199 completes a maintaining circuit for the operating coil 210 of the relay 199 which is independent of the mercury switch 22 of the frost condition responsive controller 200. This maintaining circuit may be traced from the line wire 240 through wire 254, mercury switch 208, wires 257, 258, and 271, contact 214, switch arm 211, wire 272, operating coil 210, and wire 261 back to the other line wire 241. The relay 199 will therefore remain energized until the temperature within the fixture 170 decreases to 40°.

Assume now that the temperature within the fixture 171 rises to 42° to close the mercury switch 208. A circuit is thereupon completed from the line wire 240 through wire 274, mercury switch 208 of the temperature responsive controller 197, wire 275, solenoid valve 188, and wire 276 back to the other line wire 241. Completion of this circuit therefore opens the solenoid valve 188. When the evaporators 173 and 174 are defrosted to allow the pressure therein to decrease to 35 lbs. a starting circuit for the relay 199 is completed from the line wire 240 through wire 274, mercury switch 208 of the temperature responsive controller 197, wires 278, 258, and 259, mercury switch 222, wire 260, operating coil 210, and wire 261 back to the other line wire 241. This starting circuit pulls in the relay 199 to open the solenoid valve 194 and to

start the compressor 177 in the manner pointed out above. Upon pulling in of the relay 199 a maintaining circuit therefore is completed through the mercury switch 208 of the temperature responsive controller 197 to maintain the relay 199 pulled in until the temperature within the fixture 171 decreases to 40°.

From the above it is seen that the temperature responsive controllers 196 and 197 control their respective solenoid valves 187 and 188 and act in parallel with each other and in conjunction with the frost condition responsive controller 200 to pull in the relay 199 for opening the solenoid valve 194 and for operating the compressor 177. The arrangement of Figure 4 also splits up the refrigerating system into two parts, one part including fixtures having coils which are required to be defrosted and the other part including fixtures wherein defrosting of the coils is not required. In the first part the fixtures are individually controlled in accordance with temperature and it is impossible to circulate refrigerant through the fixtures unless they have been defrosted. In the second part the fixtures are individually controlled but no defrosting action is accomplished. In addition when any fixture demands cooling the compressor is placed in operation to circulate refrigerant through the coil of that fixture and both head pressure and suction pressure protection are provided.

Although for purposes of illustration several forms of this invention have been disclosed other forms thereof may become apparent to those skilled in the art upon reference to this disclosure and therefore this invention is to be limited only by the scope of the appended claims and prior art.

I claim as my invention:

1. In a cooling system including a cooling apparatus having a cooling coil for cooling a space and means for circulating through the cooling coil a cooling fluid having sufficient cooling capacity to lower the temperature of the cooling coil below freezing whereby frosting of the cooling coil may occur, the combination with said apparatus of, valve means for controlling the circulation of cooling fluid through the cooling coil, and control means responsive to the temperature of the space and to a condition normally attendant to a defrosted state of the cooling coil for opening the valve means only upon both an increase in space temperature and the attainment of such condition.

2. In a cooling system including a cooling apparatus having a cooling coil for cooling a space and means for circulating through the cooling coil a cooling fluid having sufficient cooling capacity to lower the temperature of the cooling coil below freezing whereby frosting of the cooling coil may occur, the combination with said apparatus of, valve means for controlling the circulation of cooling fluid through the cooling coil, control means responsive to changes in space temperature for opening and closing the valve means to maintain the space temperature at desired values, and control means responsive to a condition normally attendant to a defrosted state of the cooling coil for preventing opening of the valve means by the temperature responsive control means until such condition is present.

3. In a cooling system including a cooling apparatus having a cooling coil for cooling a space and means for circulating through the cooling

coil a cooling fluid having sufficient cooling capacity to lower the temperature of the cooling coil below freezing whereby frosting of the cooling coil may occur, the combination with said apparatus of, valve means for controlling the circulation of cooling fluid through the cooling coil, control means responsive to changes in space temperature for opening and closing the valve means to maintain the space temperature at desired values, latch means for latching the valve means in a closed position, and means responsive to a condition normally attendant to a defrosted state of the cooling coil for releasing the latch means when said condition is attained.

4. In a cooling system including a cooling apparatus having a cooling coil for cooling a space and means for circulating through the cooling coil a cooling fluid having sufficient cooling capacity to lower the temperature of the cooling coil below freezing whereby frosting of the cooling coil may occur, the combination with said apparatus of, valve means for controlling the circulation of cooling fluid through the cooling coil, electromagnetic means for opening and closing the valve means, a maintaining switch closed upon opening of the valve means, a first switch, means responsive to space temperature for opening and closing the first switch, a second switch, means responsive to a condition normally attendant to a defrosted state of the cooling coil for closing the second switch when such condition exists, means for completing a starting circuit through the first and second switches and the electromagnetic means to open the valve means, and means for completing a maintaining circuit through the first switch, the maintaining switch and the electromagnetic means to maintain the valve means open until the space temperature decreases.

5. In a refrigeration system including a refrigerating apparatus having evaporator means for cooling a space and a compressor for circulating refrigerant through the evaporator means, the combination with said apparatus of, valve means on the discharge side of the evaporator means for controlling the circulation of refrigerant through the evaporator means, and control means responsive to the temperature of the space and the pressure in the evaporator means for opening the valve means upon an increase in space temperature providing the evaporator means is defrosted.

6. In a refrigeration system including a refrigerating apparatus having evaporator means for cooling a space and a compressor for circulating refrigerant through the evaporator means, the combination with said apparatus of, valve means on the discharge side of the evaporator means for controlling the circulation of refrigerant through the evaporator means, control means responsive to changes in space temperature for opening and closing the valve means to maintain the space temperature at desired values, and control means responsive to the pressure in the evaporator means for preventing opening of the valve means by the temperature responsive means until the evaporator means is defrosted.

7. In a refrigeration system including a refrigerating apparatus having evaporator means for cooling a space and a compressor for circulating refrigerant through the evaporator means, the combination with said apparatus of, valve means on the discharge side of the evaporator means for controlling the circulation of refrigerant through the evaporator means, control means responsive to changes in space temperature for opening and

closing the valve means to maintain the space temperature at desired values, latch means for latching the valve means in a closed position, and means responsive to the pressure in the evaporator means for releasing the latch means when the evaporator means is defrosted to prevent opening of the valve means by the temperature responsive control means until the evaporator means is defrosted.

8. In a refrigeration system including a refrigerating apparatus having evaporator means for cooling a space and a compressor for circulating refrigerant through the evaporator means, the combination with said apparatus of, valve means on the discharge side of the evaporator means for controlling the circulation of refrigerant through the evaporator means, electromagnetic means for opening and closing the valve means, a maintaining switch closed upon opening of the valve means, a first switch, means responsive to space temperature for opening and closing the first switch, a second switch, means responsive to the pressure within the evaporator means for closing the second switch when the evaporator means is defrosted, means for completing a starting circuit through the first and second switches and the electromagnetic means to open the valve means when the space temperature increases and the evaporator means is defrosted, and means for completing a maintaining circuit through the first switch, the maintaining switch and the electromagnetic means to maintain the valve means open until the space temperature decreases.

9. In a cooling system including a cooling apparatus having a plurality of cooling coils for cooling a plurality of spaces and a common means for circulating through the cooling coils a cooling fluid having sufficient cooling capacity to lower the temperature of the cooling coils below freezing whereby frosting of the cooling coils may occur, the combination with said apparatus of, valve means associated with each cooling coil for controlling the flow of cooling fluid through its cooling coil, and control means associated with each cooling coil and responsive to a condition normally attendant to a defrosted state of its cooling coil and the attainment of a predetermined high temperature in the space cooled thereby for opening the valve means of that cooling coil.

10. In a cooling system including a cooling apparatus having a plurality of cooling coils for cooling a plurality of spaces and a common means for circulating through the cooling coils a cooling fluid having sufficient cooling capacity to lower the temperature of the cooling coils below freezing whereby frosting of the cooling coils may occur, the combination with said apparatus of, valve means associated with each cooling coil for controlling the flow of cooling fluid through its cooling coil, control means associated with each cooling coil and responsive to the temperature of the space cooled thereby for opening and closing the valve means of that cooling coil to maintain the space temperatures at desired values whereby individual temperature control of each cooling coil is obtained, and control means associated with each cooling coil and responsive to a condition normally attendant to a defrosted state of the cooling coil thereof for preventing opening of the valve means of that cooling coil by the temperature responsive control means until such a condition has been attained.

11. In a refrigeration system including a refrigerating apparatus having a plurality of evap-

7
orator means for cooling a plurality of spaces and a common compressor for circulating refrigerant through all of the evaporator means, the combination with said apparatus of, valve means on the discharge side of each evaporator means for controlling the circulation of refrigerant therethrough, and control means associated with each evaporator means and responsive to the pressure therein and to the temperature of the space cooled thereby for opening the valve means of that evaporator means upon an increase in space temperature providing that evaporator means is defrosted whereby individual temperature and defrosting control of each evaporator means is obtained.

12. In a refrigeration system including a refrigerating apparatus having a plurality of evaporator means for cooling a plurality of spaces and a common compressor for circulating refrigerant through all of the evaporator means, the combination with said apparatus of, valve means on the discharge side of each evaporator means for controlling the circulation of refrigerant therethrough, control means associated with each evaporator means and responsive to the temperature of the space cooled thereby for opening and closing the valve means of that evaporator means to maintain the space temperature at desired values whereby individual temperature control of each evaporator means is obtained, and control means associated with each evaporator means and responsive to the pressure therein for preventing opening of the valve means of that evaporator means by the temperature responsive control means until that cooling coil is defrosted whereby individual defrosting control of each evaporator means is obtained.

13. In a cooling system including a cooling apparatus having a first cooling coil for cooling a space wherein defrosting of that cooling coil is desirable, a second cooling coil for cooling another space wherein defrosting of that cooling coil is not required and a common means for circulating cooling fluid through both cooling coils, the combination with said apparatus of, valve means for controlling the circulation of cooling fluid through the first cooling coil, and control means responsive to the temperature of the space cooled by the first cooling coil and to a condition normally attendant to a defrosted state of the first cooling coil for opening the valve means upon an increase in space temperature providing said condition has been attained.

14. In a cooling system including a cooling apparatus having a first cooling coil for cooling a space wherein defrosting of that cooling coil is desirable, a second cooling coil for cooling another space wherein defrosting of that cooling coil is not required and a common means for circulating cooling fluid through both cooling coils, the combination with said apparatus of, valve means for controlling the circulation of cooling fluid through the first cooling coil, control means responsive to an increase in the temperature of the space cooled by the first cooling coil and to a condition normally attendant to a defrosted state of the first cooling coil for opening the valve means, second valve means for controlling the circulation of cooling fluid through the second cooling coil, and control means responsive to the temperature of the space cooled by the second cooling coil for opening the second valve means upon an increase in space temperature.

15. In a refrigeration system including a refrigerating apparatus having a first evaporator means for cooling a space wherein defrosting of that evaporator means is desirable, a second evaporator means for cooling another space wherein defrosting of the evaporator means is not required and a common compressor for circulating refrigerant through both evaporator means, the combination with said apparatus of, valve means on the discharge side of the first evaporator means for controlling the circulation of refrigerant therethrough, and control means responsive to the pressure in the first evaporator means and to the temperature of the space cooled thereby for opening the valve means upon an increase in space temperature providing the first evaporator means is defrosted.

16. In a refrigeration system including a refrigerating apparatus having a first evaporator means for cooling a space wherein defrosting of that evaporator means is desirable, a second evaporator means for cooling another space wherein defrosting of the evaporator means is not required and a common compressor for circulating refrigerant through both evaporator means, the combination with said apparatus of, valve means on the discharge side of the first evaporator means for controlling the circulation of refrigerant therethrough, control means responsive to the pressure in the first evaporator means and to the temperature of the space cooled thereby for opening the valve means upon an increase in space temperature providing the first evaporator means is defrosted, second valve means for controlling the circulation of refrigerant through the second evaporator means, and control means responsive to the temperature of the space cooled by the second evaporator means for opening the second valve means upon an increase in space temperature.

17. In a cooling system including a cooling apparatus having a first cooling coil for cooling a space wherein defrosting of that cooling coil is desirable, a second cooling coil for cooling another space wherein defrosting of that cooling coil is not required and a common means for circulating cooling fluid through both cooling coils, the combination with said apparatus of, valve means for controlling the circulation of cooling fluid through the first cooling coil, control means responsive to an increase in the temperature of the space cooled by the first cooling coil and to a condition normally attendant to a defrosted state of the first cooling coil for opening the valve means, second valve means for controlling the circulation of cooling fluid through the second cooling coil, control means responsive to the temperature of the space cooled by the second cooling coil for opening the second valve means upon an increase in space temperature, and means operative upon opening of either valve means for operating the cooling fluid circulating means.

18. In a refrigeration system including a refrigerating apparatus having a first evaporator means for cooling a space wherein defrosting of that evaporator means is desirable, a second evaporator means for cooling another space wherein defrosting of the evaporator means is not re-

19. In a refrigeration system including a cooling apparatus having a cooling coil for cooling a space and means for circulating through the cooling coil a cooling fluid having sufficient cooling ca-

therethrough, control means responsive to the pressure in the first evaporator means and to the temperature of the space cooled thereby for opening the valve means upon an increase in space temperature providing the first evaporator means is defrosted, control means responsive to an increase in the temperature in the second space, valve means in control of the flow of refrigerant through the second evaporator controlled thereby, and means operative upon opening of either valve means for operating the compressor.

20. In a refrigeration system including a refrigerating apparatus having a plurality of evaporators for cooling a plurality of spaces and a common compressor for circulating refrigerant through all of the evaporators, the combination with said apparatus of, valve means associated with each evaporator for controlling the circulation of refrigerant through its associated evaporator, control means associated with each evaporator and responsive to the temperature of the space cooled thereby for opening the valve means of that evaporator upon an increase in temperature, a valve located in the common discharge from all of the evaporators for controlling the circulation of refrigerant through all of the evaporators, control means responsive to the pressure in the evaporators and to an increase in temperature in any of the spaces for opening the valve upon a call for cooling providing all of the evaporators are defrosted.

21. In a cooling system including a cooling apparatus having a plurality of cooling coils for cooling a plurality of spaces and a common means for circulating through the cooling coils a cooling fluid having sufficient cooling capacity to lower the temperature of the cooling coils below freezing whereby frosting of the cooling coils may occur, the combination with said apparatus of, valve means associated with each cooling coil for controlling the flow of cooling fluid through its cooling coil, control means associated with each cooling coil and responsive to the frost condition of its cooling coil and the temperature of the space cooled thereby for opening the valve means of that cooling coil upon an increase in space temperature providing that cooling coil is defrosted whereby individual temperature and defrosting control of each cooling coil is obtained, and means operative upon opening of any of the valve means for operating the cooling fluid circulating means.

22. In a refrigeration system including a refrigerating apparatus having a plurality of evaporator means for cooling a plurality of spaces and a common compressor for circulating refrigerant through all of the evaporator means, the combination with said apparatus of, valve means on the discharge side of each evaporator means for controlling the circulation of refrigerant therethrough, and control means associated with each evaporator means and responsive to the pressure therein and to the temperature of the space cooled thereby for opening the valve means of that evaporator means upon an increase in space temperature providing that evaporator means is defrosted whereby individual temperature and defrosting control of each evaporator means is obtained, and means operative upon opening of any of the valve means for operating the compressor.

23. In a cooling system including a cooling apparatus having a cooling coil for cooling a space and means for circulating through the cooling coil a cooling fluid having sufficient cooling ca-

capacity to lower the temperature of the cooling coil below freezing whereby frosting of the cooling coil may occur, the combination with said apparatus of, valve means for controlling the circulation of cooling fluid through the cooling coil, electromagnetic means for opening and closing the valve means, a maintaining switch closed upon opening of the valve means, a first switch, means responsive to decrease and increase in the space temperature for opening and closing the first switch, a second switch, means responsive to a condition attendant to a defrosted state of the cooling coil for closing the second switch, a third switch, means responsive to a condition normally attendant to a frosted state of the cooling coil for opening the third switch, means for completing a starting circuit through the first and second switches and the electromagnetic means to open the valve means, and means for completing a maintaining circuit through the first and third switches, the maintaining switch and the electromagnetic means to maintain the valve means open.

23. In a refrigeration system including a refrigerating apparatus having evaporator means for cooling a space and a compressor for circulating refrigerant through the evaporator means, the combination with said apparatus of, valve means on the discharge side of the evaporator means for controlling the circulation of refrigerant through the evaporator means, electromagnetic means for opening and closing the valve means, a maintaining switch closed upon opening of the valve means, a first switch, means responsive to space temperature for opening and closing the first switch, a second switch, means responsive to the pressure within the evaporator means for closing the second switch when the pressure increases to a predetermined value, a third switch, means responsive to the pressure within the evaporator means for opening the third switch when the pressure decreases to a predetermined low value, means for completing a starting circuit through the first and second switches and the electromagnetic means to open the valve means, and means for completing a maintaining circuit through the first and third switches, the maintaining switch and the electromagnetic means to maintain the valve means open independently of the second switch.

24. In a refrigeration system including a refrigerating apparatus having a plurality of evaporators and a common compressor for supplying refrigerant to said evaporators, the combination with said apparatus of, control apparatus controlling the circulation of refrigerant through one of said evaporators, said control apparatus including means responsive to a condition normally attendant to a defrosted state of said one of the evaporators for always preventing the supply of refrigerant to that evaporator under all conditions of operation until said condition nor-

mally attendant to a defrosted condition of the evaporator has been attained, and means controlling the circulation of refrigerant to the remaining evaporators.

5 25. In a refrigeration system including a refrigerating apparatus having a plurality of evaporators and a common compressor or condenser for supplying refrigerant to said evaporators, the combination with said apparatus of, means for controlling the circulation of refrigerant through one of said evaporators, said control means including means responsive to a condition normally attendant to a defrosted state of said evaporator to always prevent circulation of refrigerant thereto until such condition has been attained, and control means in control of the circulation of refrigerant through another of said evaporators irrespective of whether the same is frost-
ed or defrosted.

10 26. In a cooling system including a cooling apparatus having a cooling coil for cooling a space and means for circulating through the cooling coil a cooling fluid having sufficient cooling capacity to lower the temperature of the cooling coil below freezing whereby frosting of the cooling coil may occur, the combination with said apparatus of, valve means for controlling the circulation of cooling fluid through the cooling coil, said valve means being movable between open and closed positions, means for latching said valve means in one of its positions, means responsive to the temperature of the space and means responsive to a condition normally attendant to a defrosted state of the cooling coil, said condition responsive means being arranged to cause opening of the valve means only upon the attainment of said condition, and said temperature responsive means being arranged to cause closure of the valve means upon the attainment of a predetermined relatively low temperature in the space, one of said responsive means being operatively related to said latch means for causing the valve to move from one of its positions to the other.

15 27. In a cooling system including a cooling apparatus having a cooling coil for cooling a space and means for circulating through the cooling coil a cooling fluid having sufficient cooling capacity to lower the temperature of the cooling coil below freezing whereby frosting of the cooling coil may occur, the combination with said apparatus of, valve means for controlling the circulation of cooling fluid through the cooling coil, control means responsive to a condition normally attendant to a defrosted state of the cooling coil for opening the valve means only upon the attainment of such condition and means responsive to space temperature for causing the valve means to return to closed position upon the occurrence of a predetermined relatively low temperature in the space.

WILLIAM L. MCGRATH.

CERTIFICATE OF CORRECTION.

Patent No. 2,237,261.

April 1, 1941.

WILLIAM L. McGRATH.

It is hereby certified that error appears in the printed specification of the above numbered patent requiring correction as follows: Page 2, second column, line 45, for "65, and" read --65, 66, and--; page 8, first column, line 70, claim 18, strike out "17. In a cooling system including a cooling ap-"; page 9, first column, line 12, claim 22, after "condition" insert --normally--; and that the said Letters Patent should be read with this correction therein that the same may conform to the record of the case in the Patent Office.

Signed and sealed this 29th day of July, A. D. 1941.
